(57) **CLAIM**

The ornamental design for an accessory for an electronic device, as shown and described.

DESCRIPTION

FIG. 1 is a front perspective view of an accessory for an electronic device showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof; and,

FIG. 9 is a front perspective view thereof in an environment of use.

The broken lines depict environmental subject matter that forms no part of the claimed design.

1 Claim, 7 Drawing Sheets
